UNITED STATES PATENT OFFICE.

ANDERS ANDERSEN PINDSTOFTE, OF FREDERIKSBERG, DENMARK.

BOTTLE-CLEANING MACHINE.

No. 882,962.

Specification of Letters Patent. Patented March 24, 1908.

Application filed November 13, 1906. Serial No. 343,192.

To all whom it may concern:

Be it known that I, ANDERS ANDERSEN PINDSTOFTE, manufacturer, subject of Denmark, residing at No. 62 Frederiksberg allé, 5 Frederiksberg, Denmark, have invented new and useful Improvements in Bottle-Cleaning Machines, of which the following is a specification.

The invention relates to bottle cleaning 10 machines for simultaneously cleaning the interior and exterior of the bottles. The bottles are placed on conveyer trucks or in carriages which carry them to and from the quickly rotating brush spindles intended for 15 internal cleaning, and it has for its object to provide means by which the bottles are caused to rotate during the cleaning.

A constructional form of the invention is 20 illustrated by way of example in the accompanying drawings in which,

Figure 1 shows a side elevation of a bottle cleaning machine provided with the improved means, Fig. 2 is an end view of the machine, some parts being omitted, and 25 Fig. 3 is a detail view of one of the conveyer trucks or carriages and the device for rotating the bottles during cleaning.

Like reference numerals refer to like parts throughout the specification.

30 *a* is the frame of the bottle cleaning machine having rails *b* for the rollers or wheels of the conveyer trucks or carriages *c* each of which carries one or more bottles *d* to and from the swiftly rotating brush spindles *e* intended for the internal cleaning of the 35 bottles.

In the front of each carriage *c* is arranged a 40 guide carriage *f*, which also runs upon the rails *b* and which serves to maintain the bottles in proper alinement with the brush spindles *e*. A drawbar *g* is fixed to each carriage *c* and a drawbar *h* to each guide carriage *f*. The lower forked ends of these bars engage with a bar *j* which is inserted in a 45 chain *i*. Adjustable stops upon the bar *j* cause the drawbar and thereby the carriage to move with the chain to and from the rotary brush spindles. The chain *i* is passed around two chain wheels *k* and *l* mounted in 50 the frame *a*. The chain is fixed to the wheel *l*.

A pin *l'* upon the chain wheel *l* is connected by a rod *m* with a pin *n'* upon a disk *n*, which latter is mounted upon a vertical 55 shaft *o*. The shaft *o* is intermittently rotated by means of a constantly rotated shaft *p*,

which by means of a pinion gear and a roller friction coupling of any well known construction rotates vertical shaft *o*. The shaft *p* is driven by belt connection with the main driving shaft *q*, which is mounted in the top of the frame *a* and which is provided with loose and fixed pulleys *r*. The disk *n* is provided with two projections *s*, which alternately engage a hook *s'* at the end of an arm *t* provided with a counterweight *t'*. The arm *t* is fixed to a shaft *u* provided with a handle *u'* by means of which the hook of the arm can be thrown out of engagement with the projections *s*.

The conveyer carriages *c* are provided with bottom brushes *y* which during the cleaning bear against the bottoms of the bottles, and also with rotatable rollers or the like *v*, which support the underside of the bottles, the sides of which are supported by rotatable rollers *x* also mounted upon shafts fixed to the rear-frame of the carriage. The necks of the bottles are supported by supports *n* adjustably fixed to the front of the 70 carriage.

The frame *a* carries four uprights *z*, which support three plates 2, 3, and 4. The plate 2 carries the hollow shafts, in which the brush spindles *e* are fixed, said shafts being rotated 85 from the main driving shaft *q*, the bearings of which are carried by the plate 4. The plate 3 is adjustably fixed to the uprights *z* by means of nuts and carries two shafts 5 which are rotated from the main driving shaft *q*, 90 and which shafts carry one or more rollers or disks 6 of elastic material such as india rubber, bristles, leather or the like. The rollers or disks 6 are so formed that they will come into contact with the outer surface of 95 the bottles when the conveyer carriages have completed their forward movement, but not before, and that they will release the bottles as soon as the backward movement of the conveyer carriages commences. The rollers or 100 disks 6 may be adjusted to the size of the bottles by raising or lowering the plate 3.

The two sets of carriages, each consisting of a conveyer carriage and a guide carriage, are inserted in the chain *i* in such a manner, 105 that the one set is moved forward when the other is moving backward and vice versa.

The operation of the device is as follows: The bottles are placed in the rear conveyer carriage *c* (Fig. 1), which supports the bottles 110 in an inclined position, so that when the bottles are inserted upon the brush spindles their

axis lie above the axis of said spindles and form an angle therewith. The handle u' is then turned so that the projection s of the disk n and consequently said disk is released 5 and rotated until the second projection s comes in contact with the hook of the arm t , which again is brought in normal position by its counterweight. The rotation of the disk n is transmitted to the chain-wheel l which 10 moves the chain i , thereby causing the rear set of carriages to move forward and the forward set to move back. When the conveyer carriage moves forward with the bottles its guide carriage will guide the mouth of the 15 bottles in alinement with the brush-spindles e , and as soon as the conveyer carriage has completed the forward movement the disks or rollers 6 come into contact with the outer surface of the bottles, which latter thereby 20 are rotated in the opposite direction of the disks or rollers 6 , the result being that the bottles which are supported by the rotatable rollers v will be cleaned in every part of their interior. As soon as the backward movement 25 of the conveyer carriages commences the disks or rollers 6 release the bottles, so that the bottles are only rotated during the cleaning but not during their movement to and from the brush spindles. This is of very

great importance as thereby the risk of bottle-breakage during cleaning is reduced to a minimum. 30

I claim:

In a bottle cleaning machine having a frame provided with horizontally arranged 35 quickly rotating brush-spindles for the internal cleaning of the bottles, the combination with conveyer carriages carrying the bottles to and from said brush spindles and having rotatable rollers for supporting the 40 bottles in such inclined position that their axis lies above and forms an angle with the axis of the brush spindles, of one or more rotating cylinders of an elastic material adjustably mounted in the frame of the machine 45 above said brush spindles and being of such a size that they come into contact with and rotate the bottles, but only at the moments where the bottles are fully inserted upon the brush spindles. 50

In testimony whereof I have signed my name to this specification in the presence of two subscribing witnesses.

ANDERS ANDERSEN PINDSTOFTE.
